UNITED STATES PATENT OFFICE

106,822

DESIGN FOR A SUPPORTING BRACKET FOR ELECTRIC FANS

**Abe O. Samuels, Rochester, N. Y., assignor to
Samson-United Corporation, Rochester, N. Y.**

Application February 6, 1937, Serial No. 67,494

Term of patent 14 years

To all whom it may concern:

Be it known that I, Abe O. Samuels, a citizen of the United States, residing at Rochester, in the county of Monroe and State of New York, have invented a new, original, and ornamental Design for a Supporting Bracket for Electric Fans, of which the following is a specification, reference being had to the accompanying drawings, forming a part thereof.

Figure 1 is a top plan view of the supporting bracket for electric fans showing my new design.

Figure 2 is a front elevation thereof.

Figure 3 is a side elevation thereof.

Figure 4 is a perspective view thereof.

I claim:

The ornamental design for a supporting bracket for electric fans, as shown.

ABE O. SAMUELS.
